UNITED STATES PATENT OFFICE.

WILLIAM G. CONWAY, OF HARTFORD, CONNECTICUT.

CIRCUIT-CLOSER FOR RAIN-SIGNALS.

1,174,827.

Specification of Letters Patent. Patented Mar. 7, 1916.

Application filed February 20, 1915. Serial No. 9,656.

To all whom it may concern:

Be it known that I, WILLIAM G. CONWAY, a citizen of the United States, residing at Hartford, in the county of Hartford and State of Connecticut, have invented new and useful Improvements in Circuit-Closers for Rain-Signals, of which the following is a specification.

This invention relates to signals and more particularly to rain signals.

The principal object of the invention is to provide a simple and efficient device which is adapted particularly for household use to warn the occupant that it is raining so that windows and doors may be closed to prevent damage to furniture, curtains and other household appurtenances.

Another object of the invention is the provision of a device of this character employing a novel type of fuse or controlling member which is unaffected by ordinary moisture or humidity in the atmosphere but which will be disrupted when contacted by a few drops of water.

Still another object of the invention is to provide a device of this character which is operable upon the disrupting of the fuse or controlling member to complete a normally open electrical circuit, including a bell and a switch.

Further objects of the invention will appear as the following description is read in connection with the accompanying drawing, which forms a part of this application, and in which:—

Figure 1 is a perspective view. Fig. 2 is a longitudinal sectional view.

Referring more particularly to the drawing, 1 represents a base of any suitable material which has mounted thereon the supporting heads 2 and 3 in separated relation, as shown. The head 2 has extending therethrough an insulating sleeve 4 which projects beyond the vertical faces, as shown in Fig. 2 and at one end has secured thereto a spring retainer cap 5. This sleeve has slidably mounted therein a plunger 6 having an enlarged head 7 formed integrally therewith and to which is secured a hook 8, the purpose of which will be hereinafter described. Secured to the front face of the head 2 and arranged on opposite sides of the sleeve 4 are contact members 10 and 11 which are adapted to be bridged by the head 7 so as to complete the electrical circuit from the battery B over the wire 12, contact terminal 13,

contact 10, head 7, contact 11, contact 14, wire 15, including the switch 16 and back to the opposite side of the battery. Connecting the plunger 6 and cap 5 is a spiral spring 60 17 which normally tends to draw the head 7 into engagement with the contacts 10 and 11 so as to complete the electrical circuit, and in order to hold the head out of engagement with said contacts I provide a novel 65 type of fuse consisting of a specially treated strip of tissue or rice paper 18 provided with reinforcements 19 and 20 at opposite ends, the former having a single hole to be engaged by the hook 8 and the latter having 70 a pair of spaced holes to be engaged by the hooks 21 on the bracket 22 which is pivoted to the head 3. The length of these fuses or controlling members is such that when stretched between the bracket and the hook 75 8 they will hold the head 7 out of engagement with the contacts 10 and 11, and thus prevent the completion of the electrical circuit, the plunger 6 being electrically separated from the contacts by the sleeve 4. 80

It has been found in practice that by specially treating the controlling members or fuses that they may be rendered impervious to ordinary moistures, such as the humidity of the atmosphere prior to a rain but 85 which are rendered pervious and disruptable upon actual contact with rain.

In using the device the same is preferably placed upon a window sill and it will, of course, be understood that a plurality of 90 these devices may be connected up in parallel in an electrical circuit and placed on every window sill in the house, so that upon being contacted with rain the applicant will be notified immediately by the sounding of 95 the bell and can close the windows and doors to prevent damage to the household goods.

What is claimed is:—

A circuit closer comprising a base, supporting heads mounted upon said base and arranged in spaced relation, one of said heads being provided with a transverse opening, an insulated sleeve extending through said opening and projecting beyond the surface of said head, said sleeve being 100 105 interiorly threaded adjacent its inner extremity, a retainer top threadedly mounted in the inner extremity of said sleeve, electrical contacts mounted upon the inner extremity of the last mentioned head and encircling said opening, a tubular plunger 110 movably mounted within said sleeve and

having the inner end thereof open, an enlarged head formed on the outer extremity of said tubular plungers, a hook extending through said head and into said plunger, a coil retractile spring connecting said retainer top with said hook, a hook formed on the remaining supporting head and a disruptable strip connecting said hooks whereby

upon breaking of the same the plunger will be actuated to bridge said contacts.

In testimony whereof I affix my signature in presence of two witnesses.

WILLIAM G. CONWAY.
